SOCKET FOR TUBE-TYPE INCANDESCENT LAMPS

Filed June 13, 1952

UNITED STATES PATENT OFFICE

2,688,668

SOCKET FOR TUBE-TYPE INCANDESCENT LAMPS

Ruben P. Rosen, Philadelphia, Pa., assignor to Progress Manufacturing Company, Inc., Philadelphia, Pa., a corporation of Pennsylvania

Application June 13, 1952, Serial No. 293,415

6 Claims. (Cl. 200—51.09)

1

This invention relates generally to electrical lamp sockets and is more particularly concerned with an improved construction of an electrical socket designed to operatively receive the end of a tube type incandescent lamp.

Among the principal objects of the present invention is to provide a lampholder or socket for the end of a tube type incandescent lamp, the socket being made of a pair of parts of which one is fixed in position and the other is shiftable relative thereto for mounting and dismounting the lamp, contact elements being carried by the aforementioned parts for opening and closing the circuit to the lamp switch as the lamp is mounted and dismounted, and the contact element carried by the fixed one of the aforementioned parts being normally fixed in position relative thereto.

Still another object of the present invention is to provide such a socket wherein the contact element carried by the fixed one of the socket parts is spring pressed for movement only to take up wear.

Other objects and advantages of the present invention will appear more fully hereinafter, it being understood that the present invention consists substantially in the combination, construction, location and relative arrangement of parts, all as described in detail hereinafter, as shown in the accompanying drawings and as finally pointed out in the appended claims.

In the accompanying drawings, which are illustrative of a preferred form of the present invention:

Figure 1 is a perspective view of a tube type incandescent lamp carried by vertically spaced lamp sockets of a lighting fixture, the present invention being incorporated in the lowermost lamp socket;

Figure 2 is a side elevational view of the lowermost lamp socket shown in Figure 1, the fixed and shiftable socket parts being shown disassembled;

Figure 3 is an exploded view showing in perspective the component parts of the lowermost lamp socket;

Figure 4 is a plan section on line 4—4 of Figure 5;

Figure 5 is a sectional elevation of the lowermost lamp socket, which is shown without the lamp mounted therein;

Figure 6 is an enlarged sectional elevation on line 6—6 of Figure 8;

Figure 7 is a side elevational view on line 7—7

2

of Figure 1, parts being broken away to expose others;

Figure 8 is an enlarged elevational view on line 8—8 of Figure 2; and

Figure 9 is an enlarged elevational view on line 9—9 of Figure 2.

This invention constitutes an improvement to the lampholder or socket which is the subject of United States Letters Patent 2,554,541, issued to the applicant herein on May 29, 1951, and reference may be had to the aforementioned patent for the description and operation of all parts not specifically described herein.

Referring now more particularly to the drawings, it will be observed that the lampholder of the present invention is adapted for use in a lighting fixture as shown in Figure 1, said lighting fixture having a main supporting base 10 designed for use in conjunction with a tube-type incandescent lamp 11 the opposite ends of which are respectively received by a pair of axially spaced socket parts 12 and 13, the socket part 12 being immovably fixed in position upon the supporting base 10 of the lighting fixture, while the socket part 13 constitutes a relatively movable element of a lampholder assembly designated generally 14, constructed in accordance with and embodying the principles of the present invention.

The relatively fixed socket part 12 essentially includes a main body part 15 provided with a socket 16 adapted to receive the upper end of the tubular lamp 11. It will be understood that the socket part 12 is fixed to the mounting base 10 of the fixture with the axis of its socket 16 extending lengthwise of the fixture, that is, coincident with the axis of the tube lamp adapted to be supported between the oppositely disposed sockets 12 and 13.

The lampholder 14, of which the socket part 13 forms a component element, includes a supporting back plate 17 adapted to be fixedly secured to the supporting base 10 of the lighting fixture by a pair of screws 18—18 projected through openings 19—19 formed in the base 10 and into threaded apertures 20—20 formed in the supporting back 17. This supporting back is provided along its opposite edges with channel-shaped guideways 21—21 and at its top with a horizontally disposed plate 22 terminating in a vertically disposed flange 23. The horizontally disposed top plate 22 is provided with a pair of laterally spaced struck out portions forming a pair of spring suspension hooks 24—24

from which are respectively suspended a pair of coiled tension springs 25-25.

The socket part 13 is slidably associated with the supporting back plate 17 and is provided with a generally circular part 27 which is centrally recessed to provide a socket 28 for receiving the lower end of the tubular lamp 11, and with an integrally formed rear part 29 adapted to be slidably received within the channeled supporting back 17. It will be noted that the rear part 29 is generally of rectangular form, the opposite longitudinal edges 30-30, being respectively adapted for sliding, fit within the channels 21-21 of the fixed member 17.

Extending across the bottom end of the guided rear part 29 is a plate 31 having a pair of laterally spaced hooks 32-32 formed thereon, these hooks being extended upwardly through suitable openings 33-33 formed in the bottom end of the part 29 for respective engagement by the lower ends of the coiled extension springs 25-25.

Whereas the relatively fixed socket part 12 is internally fitted with an unswitched contact element (not shown) for electrically connecting the inserted end of the tubular lamp to a conductor (not shown) immediately upon insertion of the lamp end into the socket 16, the movable socket part 13 of the lamp holder assembly 14 is internally provided with a rotatable fixture switch as well as with an interlock switch which is operative to open the circuit to the lamp when the socket part 13 is retracted into lamp removing position. Thus, referring more particularly to Figures 3 and 5, it will be noted that the base of the socketed part 27 is centrally bored, as at 34, to receive a rotatable switch knob 35, the inner end of which is kerfed, as at 36, to receive an S-shaped contact element 37. The opposite ends of this rotatable contact element 37 are respectively adapted to engage the arcuately shaped portions 38-38 of a pair of contact members 39 and 40 fixed in the base of the socket 28, the member 40 being provided with a wing element 41 the free end of which is adapted to project upwardly through an opening 42 formed in an insulating plate 43 overlying the elements 39 and 40. The arcuately shaped parts 38-38 of these fixed contact elements 39 and 40 are disposed in diametrically opposed relation within a suitable well 44 formed in the base of the socket 28. A metal contact plate 45 overlies the insulating plate 43 and is in electrical contact with the wing element 41 projecting upwardly through the opening 42 in the intervening insulating plate 43. The plate 45 is centrally provided with a raised portion 46 adapted for contact by the metal cap (not shown) fitted on the end of the tube lamp. The several parts 35, 37, 39, 40, 43 and 45 are all secured in their fixed relation, as shown, within the base of the socket 28 by suitable securing elements, such as pins 47-47 driven into the part 27 through suitably registering apertures in the members 43 and 45.

The member 39 is provided with a lateral extension 48 projected through an opening 49 formed in the back wall portion of the socket 28. The extension 48 terminates in an upturned lip 48^a which is disposed with its outer surface flush with the back surface of the circular part 27, and which is of such size and shape as to fit snugly into the opening 49, being thus adapted to wipingly engage and make electrical contact with a main or button contact element 50 carried by a contact mounting fixedly secured to the channeled support 17.

The button contact element 50 forms a component part of the aforementioned contact mounting, which also includes a base member 51 molded or otherwise formed of insulating material. The latter is made with a plate 51^a which is generally triangular in shape, and integrally formed therewith are a pair of opposed longitudinally extending walls 52-52 joined together at one end by a transverse wall 53. The ends of the walls 52-52 remote from the wall 53 are arranged to slidably retain therebetween the main or button contact element 50, which is in the form of a cylindrical member provided with a rounded nose 54 normally positioned to project beyond the walls 52-52, the nose 54 being of such size and shape as to form a cylindrical shoulder 55 at the base thereof. Disposed between the walls 52-52 is a secondary contact element 56 having a portion thereof remote from wall 53 pressed flat against the triangular plate 51^a, and having a portion thereof proximate the wall 53 curved to position it out of contact with the triangular plate 51. The contact element 50 is provided with a central bore 57 through a major portion thereof and a coil spring 58 is disposed therein to react between the contact element 50 and the flat end of the contact element 56. The contact member 50 is shifted axially by the action of coil spring 58, but such shifting movement is limited by a pair of opposed inwardly projecting shoulders 59-59 formed respectively on walls 52-52 for coaction with the shoulder 55 on the contact element 50. The triangular plate 51^a is fixedly secured to the channeled support 17 by fastening elements 60 projected through openings 61 in the three corner portions thereof and registering openings 62 in the support 17. The contact member 56 is connected, as by soldering or welding to the terminal end of an insulated conductor wire 63.

When the tubular lamp 11 is mounted in position, as shown in Figure 1, the contact element 39 is in electrical engagement with the contact element 50 (as seen Figure 7), and in this condition of the parts the lamp may be turned on and off by rotation of the rotary switch element 37.

Upon axially shifting the socketed part 13 of the lamp holder 14 into its lamp removing position, lip 48^a of the contact element 39 moves to a position below the relatively fixed contact element 50 in consequence of which the connection to the lamp is broken. If desired, and it is generally preferable so to do, the contact element 50 is so arranged with respect to the lip 48^a, the latter being movable with the socketed part of the lampholder 14, as to provide for breaking of the circuit to the contact element 39 when the socketed part is completely free of its lamp and is thus in its uppermost position. In such case, the lip 48^a of the contact element 39 would be spaced above the contact element 50, engagement with the latter being then normally made only when the socketed part of the lampholder 14 is in lamp supporting position, as shown in Figure 7.

In assembling the lamp holder 14, contact element 50 is pressed axially inward, the coil spring 58 being thus compressed and the shoulder 55 of the contact element 50 being thus disposed in spaced relation to the pair of shoulders 59-59 formed on the longitudinally extending walls 52-52. As the lip 48^a and the contact element 50 wear due to repeated relative movement therebetween, the action of the coil spring 58 causes the contact element 50 to axially shift in order 75 to take up the same. Otherwise it will be noted,

there is no appreciable shifting movement of the contact element 50, either when the lamp 11 is placed in the lampholder or when it is removed therefrom.

It will be understood, of course, that the present invention is susceptible of various changes and modifications which may be made from time to time without involving any departure from the general principles or real spirit thereof, and it is accordingly intended to claim the same broadly, as well as specifically, as indicated in the appended claims.

What is claimed as new and useful is:

1. In a contact mounting for use in a safety interlock switch having a pair of relatively shiftable parts, a base member formed of insulating material and comprising a plate adapted to be rigidly secured to one of said parts, and a pair of walls integral with and extending outwardly from said plate in relatively spaced relation, opposed portions of said walls being provided with proximate surfaces adapted to engage the opposite sides of an elongated member extending outwardly from said plate, an elongated main contact element between the proximate surfaces of said opposed wall portions and in spaced relation to said plate, said contact element being axially shiftable and the end portion of said main contact element remote from said plate being fully exposed, elongated terminal means between said pair of walls and extending along said plate between the same and said main contact element, a coil spring between the latter and said terminal means acting to press one end portion of said terminal means against said plate and to axially shift said main contact element, and means for limiting said axial shifting of the main contact element, the opposite end portion of said terminal means being laterally spaced relative to said coil spring and main contact element and having means adapted for connection to a contact wire.

2. In a contact mounting for use in a safety interlock switch having a pair of relatively shiftable parts, a base member formed of insulating material and comprising a plate adapted to be rigidly secured to one of said parts, a pair of walls integral with said plate and disposed in relatively spaced relation, opposed portions of said walls being provided with proximate surfaces adapted to engage the opposite sides of an elongated member angularly disposed relative to said plate, and a pair of shoulders respectively integral with said walls and disposed in opposed relation to one another and in spaced relation to said plate, an elongated main contact element between the proximate surfaces of said opposed wall portions and in spaced relation to said plate, said main contact element being axially shiftable, a shoulder intermediate the ends of said main contact member, elongated terminal means between said pair of walls and extending along said plate between the same and said main contact element, and a coil spring between the latter and said terminal means acting to press one end portion of said terminal means against said plate and to axially shift said main contact element to a position wherein said shoulder intermediate the ends of the latter abuts said inwardly projecting shoulders of said pair of walls, in which position the end portion of said main contact element remote from said plate is fully exposed, the opposite end portion of said terminal means being laterally spaced relative to said coil spring and main contact element and having means adapted for connection to a contact wire.

3. In a contact mounting for use in a safety interlock switch having a pair of relatively shiftable parts, a base member formed of insulating material and comprising a plate adapted to be rigidly secured to one of said parts, and a pair of walls integral with said plate and disposed in relatively spaced relation, opposed portions of said walls being respectively provided with proximate surfaces adapted to engage diametrically opposed side portions of a cylindrical member disposed normally relative to said plate, and also being respectively provided with opposed inwardly projecting shoulders, a cylindrical main contact element between the proximate surfaces of said opposed wall portions and in spaced relation to said plate, said main contact element being axially shiftable and having a circumferential shoulder formed intermediate its ends, flat elongated means between said pairs of walls and extending flatwise along said plate between the same and said main contact element, and a coil spring between the latter and said terminal means and coaxially related to said main contact element, said coil spring acting to press one end portion of said terminal means against said plate and to axially shift said main contact element to a position wherein said circumferential shoulder of the latter abuts said inwardly projecting shoulders of said pair of walls, in which position the end portion of said main contact element remote from said plate is fully exposed, the opposite end portion of said terminal means being laterally spaced relative to said coil spring and main contact element and having means adapted for connection to a contact wire.

4. In a contact mounting for use in a safety interlock switch having a pair of relatively shiftable parts, a base member formed of insulating material and comprising a plate adapted to be rigidly secured to one of said parts, a main contact element carried by said plate and disposed in spaced relation thereto, elongated terminal means extending along said plate between the same and said main contact element yieldable means between the latter and said terminal means acting to press one end portion of said terminal means against said plate and to axially shift said main contact element away from said plate for fully exposing one end thereof, and means for limiting said axial shifting of the main contact element, the opposite end portion of said terminal means being laterally spaced relative to said yieldable means and main contact element and being adapted for connection to a contact wire.

5. In a contact mounting for use in a safety interlock switch having a pair of relatively shiftable parts, a base member formed of insulating material and comprising a plate adapted to be rigidly secured to one of said parts, and a pair of walls integral with and extending outwardly from said plate in relatively spaced relation, opposed portions of said walls being provided with proximate surfaces adapted to embrace the opposite sides of a contact member extending outwardly from said plate, a main contact element having an outer portion thereof disposed between the proximate surfaces of said opposed wall portions and in spaced relation to said plate, said outer portion of the contact element being shiftable relatively to said socket and having an extremity which projects freely from said socket and is normally fully exposed, elongated terminal means between said pair of walls and extending along said plate between the same and

said main contact element, said contact element being normally spring biased to effect yielding engagement of its outer extremity with a contact carried by the other of said relatively shiftable parts, said plate having an opening therein in communication with the space between the walls thereof, and a conductor wire projected through said opening and electrically connected to said terminal means.

6. In a contact mounting for use in a safety 10 interlock switch having a pair of relatively shiftable parts, a base member formed of insulating material and comprising a plate adapted to be rigidly secured to one of said parts, said plate having an elongated socket presenting away from the part to which said base is secured and toward the other of said relatively shiftable parts, a contact element yieldably disposed in said socket with its outer end projecting externally of said socket for yieldable contacting engagement with 20 a contact carried by said other relatively shift-

able part, said contact element being constrained by the socket in which it is disposed against movement other than toward and away from said base, said yieldably disposed contact element having terminal means extending therefrom along the bottom wall of said socket and overlying an opening in said bottom wall of the socket, and a conductor projected into said socket through said bottom wall opening thereof and electrically connected to said terminal means.
